CLAIM

The ornamental design for an audio device, as shown and described.

DESCRIPTION

FIG. 1 is a bottom front right perspective view of an audio device showing our new design;

FIG. 2 is a front view of the design shown of FIG. 1;

FIG. 3 is a rear view of the design shown of FIG. 1;

FIG. 4 is a left side view of the design shown of FIG. 1;

FIG. 5 is a right side of the design shown of FIG. 1;

FIG. 6 is a bottom view of the design shown of FIG. 1; and,

FIG. 7 is a top view of the design shown of FIG. 1.

The broken lines shown in the figures are included for the purpose of illustrating portions of the audio device that form no part of the claimed design.
